[57] **CLAIM**

The ornamental design for a multi-purpose portable hook and rack assembly, as shown.

DESCRIPTION

FIG. 1 is a perspective view of a multi-purpose portable hook and rack assembly with the hooks extended showing my new design therefor;

FIG. 2 is a left side elevational view, the right side elevational view being a mirror image thereof;

FIG. 3 is a front elevational view;

FIG. 4 is a rear elevational view;

FIG. 5 is a top plan view;

FIG. 6 is a bottom plan view;

FIG. 7 is a perspective view of a multi-purpose portable hook and rack assembly with the hooks in their folded configuration;

FIG. 8 is a left side elevational view, the right side elevational view being a mirror image thereof;

FIG. 9 is a front elevational view, the rear elevational view being a mirror image thereof; and,

FIG. 10 is a top plan view, the bottom plan view being a mirror image thereof.

FIG. 6

FIG. 8

FIG. 7

FIG. 9

FIG. 10
